(57) **CLAIM**

The ornamental design for trousers, as shown and described.

DESCRIPTION

FIG. 1 is a front view of the trousers, showing my new design;

FIG. 2 is a rear view of the design illustrated in FIG. 1; FIG. 3 is a rear view of the design illustrated in FIG. 1 with a zippered panel partially opened;

FIG. 4 is an enlarged fragmentary top and right perspective view of an upper portion of the design illustrated in FIG. 1 with a slit in the waist area of the trousers expanded and the zippered panel opened;

FIG. 5 is a top perspective view of the design illustrated in FIG. 1 with the slit in the waist area of the trousers closed and the zippered panel closed, the left side view being identical; and,

FIG. 6 is a top and right side perspective view of the design illustrated in FIG. 1 with the slit in the waist area of the trousers expanded and the zippered panel opened, the left side view being identical.

The tonal grey shaded portions on the inside of the trousers and on the side gusset of the trousers are to provide contrast only and do not indicate a color or a type of material of the claimed design.

The small evenly spaced dotted lines on the pants represent claimed stitching. The broken line at the end of the legs in FIG. 4 represent a symbolic break for the fragmentary view and forms no part of the claimed design.

1 Claim, 6 Drawing Sheets
